UNITED STATES PATENT OFFICE.

JAMES M. DENNIS AND HARRY R. DENNIS, OF RICHMOND, INDIANA, AS-SIGNORS TO NEW CASTLE ELECTRIC SIGN COMPANY, OF NEWCASTLE, INDIANA.

ADVERTISING-SIGN.

No. 851,074.

Specification of Letters Patent.

Patented April 23, 1907.

Application filed July 13, 1906. Serial No. 326,049.

To all whom it may concern:

Be it known that we, JAMES M. DENNIS and HARRY R. DENNIS, citizens of the United States, residing in the city of Richmond, in the county of Wayne, and in the State of Indiana, have invented new and useful Improvements in Advertising-Signs, of which the following is a full, clear, and exact description and specification, being such as will enable others skilled in the art to which it appertains to make and operate the same.

Our invention relates to day and night signs, and the object of our present invention, briefly stated, is the provision of a sign especially adapted to hang out across a sidewalk or otherwise, with special provisions whereby the letters thereon will be plainly visible during the day, while at night they will stand out boldly distinct from the body of the sign, thereby providing both a day and night sign in one construction.

Further objects, specifically stated, is to provide a sign having means for the electrical illumination thereof; to provide a sign which will allow the air to circulate therethrough thereby preventing the wind from swinging the sign or having any appreciable effect thereon; to provide novel and secure means for attaching the letters to the sign body; and to provide a sign which will be very light in weight, strong and durable in construction, and at the same time will be very efficient and attractive in appearance.

Our invention contemplates a very simple, attractive, and effective advertising sign having several novel features which will otherwise be particularly pointed out, and the preferred embodiment of our invention is shown most clearly in the accompanying drawings, in which—

Figure 1 is a diametrical cross sectional view of our sign. Fig. 2 is a front elevation of one of the two faces of our sign. Fig. 3 is a detail view illustrating the manner in which the letters are securable in position. And Fig. 4 is a detail perspective view of one of the mirrors, or reflectors, and its holder.

Similar indices denote like parts throughout the several views.

In order that our invention may be fully understood and its construction and application properly comprehended we will now take up the description thereof in detail, in which

we will describe the several parts and their relations as briefly and as compactly as we may.

The frame of our sign comprises the two inner circular rims 1 and 2; and the two outer corresponding circular rims 3 and 4. The inside diameter of the two pairs of said rims are the same, but the outer rims have a larger outside diameter than the inside rims, the peripheries of the outer rims being scalloped to the outside diameter of the inner rims.

Disposed across the space inclosed by the rims 1 and 3 are two layers of (copper) screen-wire, designated by numerals 5 and 6, the two contacting with each other, and the rims 1 and 3 are rigidly secured together with the screens 5 and 6 secured therebetween. And in like manner there is disposed across the space inclosed by the rims 2 and 4 the two layers of (copper) screen-wire, designated by the numerals 7 and 8, the two contacting with each other, and the rims 2 and 4 are rigidly secured together with the screens 7 and 8 secured therebetween.

The numeral 14 denotes a metal band which is of a width such as to space the two sets of rims the desired distance apart. Said band is formed endless and its inner circumference is the same as the outer circumference of the rims 1 and 2 over which it is placed as shown, with its edges positioned against the inner faces of the rims 3 and 4 as indicated.

The two sides of the sign are further connected by a plurality of stay-strut bolts, indicated by the letters *a*, *b*, *c*, *d*, *e*, *f*, *g*, and *h*, said bolts pass through and connect the rims 3 and 4 and they are located outside the band 14, each bolt being provided with double nuts on each end thereof in order to clamp upon the rims 3 and 4, whereby the rims may be held at the desired point with reference to each other.

The numerals 9 and 10 designate two identical disks, each having a central aperture therethrough to receive the respective outer projecting ends of the T-fitting 12.

A central horizontal aperture is formed through the screens 5, 6, 7 and 8 to receive the outer ends therein of the fitting 12, and the said fitting is placed between the two pairs of screens as shown, and the disks 9 and 10 are placed on the center of the respective outer screens, the disks are then pressed

toward each other to cause the respective outer ends of the fitting 12 to project therethrough, which of course will stretch the wire-screens to the desired tension.

5 The outer end portions of the fitting 12 are threaded both externally and internally, and the disks are secured in place as shown by reason of the nuts 11 and 13 which are run on the ends of the fitting 12 after the disks 9 and 10 have been brought to position.

The upward projecting branch of the fitting 12 is internally threaded to receive the pipe 15 which extends up therefrom through an aperture formed therefor in the band 14, 15 from which it may extend to any convenient point in order to support the sign.

The numerals 16 and 17 denote the two tubes projecting out oppositely from the fitting 12 into which they are threaded. Telescopically mounted in the tubes 16 and 17 are the respective hollow arms 18 and 19, each having on its outer end an electric light socket 20 and 21, respectively. Detachably secured in the said sockets are the respective lamps 22 and 23. Extending from each of said sockets is a pair of electric-wires, 24 and 25, which wires extend inward to the fitting 12 and from thence up through the pipe 15 to the source of electric supply.

30 Each of the lamps 22 and 23 is provided with a mirror reflector designated by the numerals 26 and 27, respectively, said mirrors have each a perfectly flat face directed to its respective lamp and to the faces of the sign, said mirrors being oppositely disposed and each is retained in position by arms 28 and 29, respectively, said arms being connected at their outer ends to the peripheries of their respective reflectors and from thence 35 converging inwardly toward and connected to their respective collars 30 and 31, said collars being disposed snugly around the necks of the respective lamps 22 and 23.

One of the important features of this invention which we desire to accentuate is the means we employ for securing the letters, removably, in place, which is shown most clearly in Fig. 3, in which view the numeral 32 designates a letter. The letters desired 40 for a particular sign are first formed of sheet metal, and at a plurality of points in their peripheries are cut in two diverging incisions, commencing at a common point on the periphery of the letter and extending inwardly 45 the desired distance that the tongues should be in length. Said tongues are designated by the numeral 33, and they are deltoid or acuminate in contour with their points directed outward. After said incisions are 50 made the tongues formed thereby are bent back at right-angles to the letter and the letter is then laid in position on the face of the screen with the said tongues projecting through the meshes of the two thicknesses of 55 screen; after which the tongues are bent back

parallel with the screen to as near their original position as is possible, thereby locking the letter in place substantially as shown.

The letters of the sign, and also the outer rim, should be made of or at least faced with 70 aluminium or some other light reflecting material or paint in order to receive and transmit the light directed thereon by the mirror, or mirrors, at the same time we color the screen wire or gauze a dead black in order to provide a proper background for the letters, 75 both for day and for night, that is whether the letters are illuminated or not.

It is apparent that although both sides of the sign are formed concave yet the letters are 80 all attached to an approximately flat surface and are all on the same inclination, that is, directed toward the respective lamps.

By reason of the telescoping arms carrying the lamps we provide means for focusing the 85 reflected light from the mirrors properly upon the letters and the outer rim, which by the way are the only parts which will be visible at night when the lamps are lighted, and the mirrors we find will greatly increase the intensity of the light from the lamps, distributing the light equally to all the letters, and to all parts of each letter, causing each letter to appear bold and distinct.

If desired the letters may be shaded by 95 paint or the like which may be deposited on the faces of the screens, which paint or shading should be of a color distinctive from the background or the letters.

It is apparent that the lamp-bulbs may be 100 clear or of any desired color, or even of two or more colors in order to give different effects in appearance, for instance: The bulb of the lamp may be red in color, giving a red effect to the illuminated letters, or the bulb 105 may be of two colors, divided in an axial direction, thereby giving a two color effect to the letters, and also the lamps may be turned whereby the different colors may be changed from one part of the sign to another.

Having now fully shown and described our invention, what we claim and desire to secure by Letters Patent of the United States, is—

1. A sign comprising two double and circular rims spaced apart, a double screen secured between the said rims and converging inward to near their centers, a band dividing the pairs of rims, bolts connecting the two outer rims in order to adjust the pairs of rims in their relations to each other, a pair of oppositely disposed disks contacting each with the face of its screen and disposed over the center thereof, a T-fitting connecting the centers of the disks and extending therethrough, nuts threaded on the outer extensions of said fitting to retain the disks in position, a tube extending out from each horizontal portion of said fitting, an arm telescopically mounted in each of said tubes, an electric lamp carried on the outer end of each 130

of said arms, a pipe extending from said fitting through the edge of the sign, a wire circuit extending from each lamp through said arms and tubes, respectively, and through 5 said fitting and pipe, and means for directing the light from said lamps onto the face of the sign, all substantially as shown and described.

2. A sign comprising two double and circular rims spaced apart, a double screen secured between said rims and converging inward to near their centers, a band dividing the pairs of rims, bolts connecting the two outer rims in order to adjust the pairs of rims in their 15 relations to each other, a pair of oppositely disposed disks contacting each with the face of its screen and disposed over the center thereof, a T-fitting connecting the centers of the disks and extending therethrough, nuts 20 threaded on the outer extensions of said fittings to retain the disks in position, a tube extending out from each horizontal portion of said fitting, an arm telescopically mounted in each of said tubes, an electric lamp carried 25 on the outer end of each of said arms, a pipe extending from said fitting through the edge of the sign, a wire circuit extending from each lamp through said arms and tubes, respectively, and through 30 said fitting and pipe, letters attached to said wire screens, and a mirror carried in front of each of said lamps and being so positioned as to direct the light from the lamps upon the letters of the respective screens, all substantially as shown and 35 described.

3. A sign comprising two double and circular rims spaced apart, a double screen secured between said rims and converging inward to near their centers, a band dividing 40 the pairs of rims, bolts connecting the two outer rims in order to adjust the pairs of rims in their relations to each other, a pair of oppositely disposed disks contacting each with the face of its screen and disposed over 45 the center thereof, a T-fitting connecting the centers of the disks and extending therethrough, nuts threaded on the outer extensions of said fitting to retain the disks in position, a tube extending out from each horizontal 50 portion of said fitting, an arm telescopically mounted in each of said tubes, an electric lamp carried on the outer end of each of said arms, a pipe extending from said fitting through the edge of the sign, a wire 55 circuit extending from each lamp through said arms and tubes, respectively, and through said fitting and pipe, mirrors carried in front of said lamps for directing the light from the lamps onto the faces of said wire- 60 screens, and letters attached to faces of said wire-screens by tongues formed in the edges of the letters, the said tongues being formed by cutting two incisions inward divergently from a common point on the periphery of the 65 letters, said tongues being bent back at right

angles to the letters and inserted through the meshes of the screen and then bent back to near their original positions, all substantially as shown and described and for the purposes set forth.

4. An advertising sign comprising double circular rims spaced apart, a wire-screen secured between each of said double rims and converging inwardly, a band dividing the pairs of rims and their screens, means for connecting the rims to said band, a disk contacting with the center of the face of each screen, a T-fitting connecting said disks and extending therethrough, nuts threaded on the protruding ends of said fitting and contacting with the faces of the respective disks, a tube extending out from each horizontal portion of said fitting, an arm telescopically mounted in each of said tubes, a lamp carried 75 on the outer end of each of said arms, a pipe 80 extending from said fitting through the edge of the sign at right angles to said tubes, feed wires extending to said lamps, a mirror disposed in front of each of said lamps to direct the light therefrom onto the respective 85 faces of the screens, metal letters attached to the faces of each of said screens by tongues cut in the peripheries of the letters and adapted to be inserted through the meshes of the screens and then bent parallel with the 90 letters and the screens, all substantially as 95 shown and described.

5. An advertising sign comprising in combination two circular rims spaced apart, a screen carried by each of said rims and formed concave, a disk contacting with the center portion of the face of each screen, a T-fitting connecting said disks, a nut threaded on each of the outer extensions of said fitting and contacting with the outer faces of said 100 disks, a lamp carried some distance out from the face of each of said disks, means whereby said lamps may be adjusted to and from said disks, feed wires extending through the sign to said lamps, a mirror carried with each of 105 said lamps and adapted to direct the light from the lamps onto the faces of said screens, metal letters secured to each of said screens, said letters being of a color distinctively different from the color of the screens, means 110 for securing said letters to the screens which means consists in forming tongues at various points in the peripheries of the letter, each of said tongues being formed by cutting two incisions inward divergently from a common 115 point in the periphery of the letters, said tongues being adapted to be bent back and inserted through meshes of the screen and then bent parallel with the screen and the letter, all substantially as shown and described.

6. A sign comprising double rims spaced apart, screens secured at their edges by the respective double rims and converging inward toward each other, means for dividing said rims and screens, means for retaining said 120

1 rims and screens in proper relations to each other, oppositely disposed disks contacting with the center portion of their respective screens, a T-fitting connecting said disks and 5 opening outwardly at the center of each screen with its center portion opening in the space between the screens, means for retaining said disks in contact with the screens, tubes extending outwardly from each end of 10 said T-fitting, a lamp carried on the outer end of each of said arms, a reflector carried in front of each of said lamps and directed

toward its respective screen, and letters attached to the face of each screen by tongues cut in the letters.

15 In testimony whereof we have hereunto signed our names to this specification in the presence of two subscribing witnesses.

JAMES M. DENNIS.
